UNITED STATES PATENT OFFICE

151,630

DESIGN FOR A PHONOGRAPH TONE ARM

Charles A. Geib, Chicago, Ill., assignor to The Norwood Company, Chicago, Ill., a corporation of Illinois

Application September 13, 1947, Serial No. 141,378

Term of patent 14 years

(Cl. D26—14)

To all whom it may concern:

Be it known that I, Charles A. Geib, a citizen of the United States, residing at Chicago, in the county of Cook and State of Illinois, have invented a new, original, and ornamental Design for Phonograph Tone Arm of which the following is a specification, reference being had to the accompanying drawing, forming a part thereof.

In the drawings:

Figure 1 is a top perspective view of a phonograph tone arm, showing my new design;

Figure 2 is a bottom plan view;

Figure 3 is a side elevational view;

Figure 4 is a rear elevational view; and

Figure 5 is a front elevational view.

I claim:

The ornamental design for a phonograph tone arm, substantially as shown.

CHARLES A. GEIB.
